US0D1087597S

(12) United States Design Patent (10) Patent No.: US D1,087,597 S
(45) Date of Patent: * Aug. 12, 2025

(54) PILL BOX

(71) Applicant: Apothecary Products, LLC,
Burnsville, MN (US)

(72) Inventors: Daniel Darst, Zimmerman, MN (US);
Julia Olson Augdahl, Prior Lake, MN
(US)

(73) Assignee: Apothecary Products, LLC,
Burnsville, MN (US)

() Term: 15 Years

(21) Appl. No.: 29/939,438

(22) Filed: Apr. 26, 2024

(51) LOC (15) Cl. 03-01

(52) U.S. Cl.

USPC D3/203.3

(58) Field of Classification Search
